UNITED STATES PATENT OFFICE.

NETTIE J. SOLOMON, OF PEKIN, ILLINOIS.

HEN'S NEST.

1,024,372.

Specification of Letters Patent. Patented Apr. 23, 1912.

Application filed June 4, 1910. Serial No. 564,993.

To all whom it may concern:

Be it known that I, NETTIE J. SOLOMON, a citizen of the United States, residing at Pekin, in the county of Tazewell and State 5 of Illinois, have invented new and useful Improvements in Hens' Nests, of which the following is a specification.

The present invention provides a nest which may be advantageously used in the 10 raising of poultry so as to insure the hatching of a healthy brood and at the same time preserving the health of the mother hen and adding materially to her comfort and enabling the maintenance of sanitary conditions, with the result that vermin may be 15 prevented from multiplying and quickly destroyed at an opportune time, the nest being of open construction and enabling air to circulate freely therethrough and light to 20 gain access to every part thereof.

A further purpose of the invention is the provision of a nest which is light, durable and capable of being cheaply constructed and easily maintained in a sanitary condition, since it may be subjected to a liquid 25 bath or to the flames of a torch or fire without being injured in the least and with the result that all parasites, bacilli and other insect life is thoroughly destroyed.

30 The invention consists of the novel features, details of construction and combination of parts, which hereinafter will be more particularly set forth, illustrated in the accompanying drawing, and pointed out in 35 the appended claim.

Referring to the drawing, forming a part 40 of the application, Figure 1 is a perspective view of a nest embodying the invention. Fig. 2 is a transverse section of the nest, 45 showing the suspending hooks engaged over supports. Fig. 3 is a detail view, showing the manner of connecting the bottom and sides to the lower ring. Fig. 4 is a sectional detail of the upper ring, the 50 binder and a portion of the sides of the body.

Corresponding and like parts are referred 55 to in the following description, and indicated in all the views of the drawing, by the same reference characters.

It is to be understood that the nest is of proper size according to the specific use for which it is intended and comprises a body

portion and a cover. The nest is formed of metal so as to be both durable and light in 55 construction.

The body of the nest comprises an upper ring 1, a lower ring 2, a bottom 3 and sides 4. The rings 1 and 2 are formed of stout wire or light metal bars bent into circular 60 form and having their ends welded or joined in any manner. The bottom 3 is formed of wire fabric cut to proper size and having the ends of the strands bent about the ring 2 a number of times to insure the formation 65 of a substantial connection. The meshes of the fabric are sufficiently large to insure free circulation of air and the escape of foreign matter. The sides 4 consist of meshed fabric, the strands of which are secured to the 70 upper ring 1 and the lower ring 2. The lower ends of the strands are wrapped about the lower ring 2, whereas the upper ends of the strands are passed over the upper ring 1 and are twisted about a binder 5, which 75 consists of one or more strands encircling the upper portion of the sides beneath the ring 1. The binder 5 is of circular form and of less diameter than the ring 1 so as to engage the lower side of said ring and prevent the lower ends of the strands from being 80 drawn back over the ring 1 when the nest is subjected to strain when in service.

Suspending loops 6 are formed of stout 85 wire and are located at opposite points and have their lower ends secured to the ring 2 by being bent about the same a number of times. The loops are interlaced with the meshes of the sides 4 and their upper ends terminate in outer hooks 7 which engage 90 over the binder 5 and are adapted to hold the nest in suspension by engaging over suitable supports 8, which may consist of bars, beams or like means. The suspending loops 6 besides forming means for holding the nest 95 in suspension also provide handles whereby the nest may be easily and conveniently carried when required.

The cover consists of a ring 9 and a top 10. The ring 9 is of the same diameter as 100 the ring 1 and the top 10 consists of wire fabric, the strands of which are bent about the ring 9. The cover is secured to the body of the nest by means of hooks 11, the latter consisting of wire loops which have one end 105 looped about members of the meshes of the

sides, the opposite ends of the loops being bent to form hooks which engage over the ring 9 and retain the cover in place. One of the hooks is bent about the ring 9 and 5 serves to hingedly connect the cover to the body, the other hook serving as a catch to retain the cover in place when closed.

From the foregoing description, taken in connection with the accompanying drawing, 10 the advantages of the construction and of the method of operation will be readily apparent to those skilled in the art to which the invention appertains, and while I have described the principle of operation of the 15 invention, together with the device which I now consider to be the embodiment thereof, I desire to have it understood that the device shown is merely illustrative, and that such changes may be made when desired as 20 are within the scope of the claim appended hereto.

Having thus described the invention what is claimed as new, is:—

A hen's nest comprising upper and lower rings, a meshed fabric forming the bottom 25 and sides of the nest, the said bottom and sides being secured to the lower ring and the said sides having the upper edge of the fabric passing through the upper ring, thence over and around the same, a ring of 30 lighter material than the upper ring having the upper edge portion of the fabric bent around the same and engaging under the said upper ring, and loops interlaced with the fabric forming the sides of the nest and 35 having their lower ends bent around the lower ring and their upper ends outwardly curved to form suspending hooks and handles.

In testimony whereof I affix my signature 40 in presence of two witnesses.

NETTIE J. SOLOMON.
